(57) **CLAIM**

The ornamental design for a wall-mounted switch, as shown and described.

DESCRIPTION

FIG. 1 is a front, right and bottom side perspective view of a wall-mounted switch showing my new design;

FIG. 2 is a front elevational view thereof;

FIG. 3 is a right side elevational view thereof;

FIG. 4 is a left side elevational view thereof;

FIG. 5 is a bottom plan view thereof; and,

FIG. 6 is a top plan view thereof.

The broken lines in the drawings illustrate features of the wall-mounted switch that form no part of the claimed design.
